UNITED STATES PATENT OFFICE

143,370

DESIGN FOR A DUAL MOTOR POWER UNIT

Ray F. Thornton, Dearborn, Mich.

Application December 21, 1944, Serial No. 117,400

Term of patent 3½ years

(Cl. D55—1)

To all whom it may concern:

Be it known that I, Ray F. Thornton, a citizen of the United States, residing at Dearborn, Wayne County, Michigan, have invented a new, original, and ornamental Design for a Dual Motor Power Unit, of which the following is a specification, reference being had to the accompanying drawings, forming a part thereof, in which:

Fig. 1 is a perspective view of one end and a side of a dual motor power unit embodying the design of the present invention.

Fig. 2 is a perspective view taken from the opposite end of the power unit shown in Fig. 1.

Fig. 3 is a side elevation showing the opposite

side of the power unit from that shown in Figs. 1 and 2.

Fig. 4 is a sectional view taken substantially on the line 4—4 in the direction of the arrows of Fig. 3.

Figs. 2, 3 and 4 are shown on a smaller scale than that shown in Fig. 1.

The present application is a continuation in part of co-pending application, Serial No. D-113,164, filed April 6, 1944.

I claim:

The ornamental design for a dual motor power unit, as shown and described,

RAY F. THORNTON.
